UNITED STATES PATENT OFFICE.

JOHN G. SCHLENTER, OF TOLEDO, OHIO.

VACUUM MASSAGE DEVICE.

1,226,702.

Specification of Letters Patent. Patented May 22, 1917.

Application filed April 7, 1913. Serial No. 759,436.

To all whom it may concern:

Be it known that I, JOHN G. SCHLENTER, a citizen of the United States, residing at Toledo, in the county of Lucas and State of Ohio, have invented certain new and useful Improvements in Vacuum Massage Devices; and I do hereby declare the following to be a full, clear, and exact description of the invention, such as will enable others skilled in the art to which it appertains to make and use the same.

This invention has reference to vacuum massage devices and it has for its object to provide a simple, inexpensive and effective device of this character which shall be capable of applying a vacuum for massage purposes without the employment of water, electric or mechanical power.

The invention as constructed is extremely compact and may be packed into a minimum space for the purpose of shipment or for carrying in a traveling bag or other receptacle while on a journey.

To this end the invention embodies the novel combination, arrangement and details of construction hereinafter shown, described and claimed.

In the accompanying drawings illustrative of the invention, Figure 1 is a view of the complete device, partly in section, showing the vacuum creating member and a vacuum cup or applicator at the end of a flexible tube connecting with said member. Fig. 2 is a bottom view of the vacuum creating member showing the elastic diaphragm. Fig. 3 is a detail showing the means for coupling the flexible connection carrying the vacuum cup with the vacuum creating member to insure a tight joint.

Referring to the details, the vacuum creating member comprises a cup-shaped metal shell 1 over the open mouth of which is stretched an elastic diaphragm 2 of gum rubber, there being a sheet metal holding ring 3 between which and the margin 4 of the shell the margin of the diaphragm is firmly held. 5 is a tube connecting with the interior of the shell at 6 and the outer portion 7 of said tube is bent at an angle and the extreme end is made flaring, as at 9, to adapt the device for application to deep seated or wrinkled portions of the face, as for instance the portions immediately adjoining the nose and the eyes. It will be un-

derstood that to create a vacuum it is simply necessary to hold the cup-shaped shell between the thumb and fingers, with the thumb resting upon the elastic diaphragm. By pressing the diaphragm and then releasing it a vacuum is created, the extent of the vacuum depending upon the depth to which the elastic diaphragm is depressed, being greatest when the diaphragm is depressed to the full depth of the metal shell and then released. By varying the initial pressure upon the diaphragm before it is released the vacuum may be increased or decreased at pleasure.

For the purpose of application to the cheeks, bust or other broad expanses of skin surface, it is desirable to use a larger cup than that of the end 9 of the tube 5 for the purpose of giving greater suction. It is also desirable that the cup have an unhampered movement over the expanded surfaces. I therefore provide an enlarged cup 10 or applicator having a nipple 11 to attach the same to the flexible tubular connection 12, and into the opposite end of the flexible connection 12 is inserted a nipple 13 having a screw end 14 adapted to be screwed into the end 9 of the tube 5, the end 9 being internally threaded for that purpose, 15 being a soft rubber washer on the nipple 13 adapted to seat upon the flaring margins of the end 9 and insure a tight joint.

Thus the device may be used with equal facility for massaging expanded, smooth skin surfaces or depressed or wrinkled portions.

What I claim, is—

In a massage device, a hollow shell of approximately semi-spherical formation, and having an open mouth, an elastic diaphragm disposed over and completely closing the mouth of the shell, said shell being formed with an outlet at a point farthest removed from the diaphragm, the full surface of the diaphragm being disposed for manual manipulation to expel any desired volume of air from the shell through the outlet.

In testimony whereof, I hereunto affix my signature, in presence of two witnesses.

JOHN G. SCHLENTER.
